[57] CLAIM

The ornamental design for a helical spring retracting tool, as shown and described.

DESCRIPTION

FIG. 1 is a perspective view of a helical spring retracting tool showing my new design with a shock absorber

and an operating lever shown in broken line for illustrative purposes only;

FIG. 2 is a side view of the helical spring retracting tool illustrated in FIG. 1;

FIG. 3 is a top view of the helical spring retracting tool illustrated in FIG. 2;

FIG. 4 is a front view of the helical spring retracting tool;

FIG. 5 is a rear view of the helical spring retracting tool;

FIG. 6 is a side view of the helical spring retracting tool opposite to the side view illustrated in FIG. 2;

FIG. 7 is a bottom view of the helical spring retracting tool;

FIG. 8 is a perspective view of an alternative embodiment of the helical spring retracting tool;

FIG. 9 is an end view of the helical spring retracting tool shown in FIG. 8;

FIG. 10 is an opposite end view to that shown in FIG. 9;

FIG. 11 is a front view of the helical spring retracting tool shown in FIG. 8;

FIG. 12 is a top view of the helical spring retracting tool shown in FIG. 8; and

FIG. 13 is a bottom view of the helical spring retracting tool shown in FIG. 8.
